US0D1109193S

(12) **United States Design Patent** (10) **Patent No.:** **US D1,109,193 S**
(45) **Date of Patent:** **** Jan. 13, 2026**

(54) **TRACTOR**

(71) Applicant: **CLAAS KGaA mbH**, Harsewinkel (DE)

(72) Inventors: **Natalie Mildt**, Versmold (DE); **Markus Matthies**, Bielefeld (DE)

(73) Assignee: **CLAAS KGaA mbH**, Harsewinkel (DE)

(**) Term: **15 Years**

(21) Appl. No.: **29/886,958**

(22) Filed: **Mar. 15, 2023**

(30) **Foreign Application Priority Data**

Sep. 16, 2022 (EM) 009176274

(51) **LOC (15) Cl.** **15-03**

(52) **U.S. Cl.**

USPC **D15/31**

(57) **CLAIM**

The ornamental design for a tractor, as shown and described.

DESCRIPTION

FIG. 1 is a first front perspective view;

FIG. 2 is a front view;

FIG. 3 is a rear view;

FIG. 4 is a left side view;

FIG. 5 is a right side view;

FIG. 6 is a top view; and,

FIG. 7 is a second front perspective view.

The broken line portion of the figure drawings is included to show portions of the tractor that form no part of the claimed design.

The dash dot dash broken lines represent a boundary, and form no part of the claimed design.

1 Claim, 7 Drawing Sheets
